CASING FOR A HUMIDIFIER

Dana W. Mox, Glenview, Ill., assignor to Research Products Corporation, Madison, Wis.

Filed Aug. 12, 1971, Ser. No. 171,419

Term of patent 14 years

Int. Cl. D23—99

U.S. Cl. D23—147

Fig. 1

Fig. 3

Fig. 2

FIG. 1 is a front perspective view of a casing for a humidifier showing my new design;

FIG. 2 is a top plan view thereof; and

FIG. 3 is a left side elevation thereof. The rear, not shown, is open.

I claim:

The ornamental design for a casing for a humidifier, as shown and described.
